H. BRUCKER

SPOOL

Filed Feb. 24. 1927

INVENTOR.

Henry Brucker,
BY Everett Cook,
ATTORNEYS.

UNITED STATES PATENT OFFICE.

HENRY BRUCKER, OF NEWARK, NEW JERSEY, ASSIGNOR TO AMERICAN ALUMINUM WARE COMPANY, A CORPORATION OF NEW JERSEY.

SPOOL.

Application filed February 24, 1927. Serial No. 170,577.

This invention relates in general to spools and particularly to spools adapted for use in the steaming and soaking of fabric in the course of manufacture. It is essential 5 that such spools be strong and uninjured by moisture and at the same time permit circulation of liquid and air through them and the fabric wound thereon.

One object of the present invention is to 10 provide a spool of this character which embodies novel and improved features of construction which ensure strength, simplicity and cheapness in manufacture, and durability.

Other objects are to provide a spool of 15 the character described comprising a minimum number of simple and strong parts which can be easily and quickly assembled; to provide such a spool including a tubular 20 body, end plates and means for clamping said end plates together and to said body, said parts being of novel and improved construction whereby the body is securely clamped between the end plates against 25 movement in all directions and said end plates are held in fixed relation to each other; to provide a novel and improved method of making a spool, and to obtain other results and advantages as may be 30 brought out by the following description.

Referring to the accompanying drawings, in which corresponding and like parts are designated throughout the several views by the same reference characters,

Figure 1 is a side elevation of a spool embodying the invention;

Figure 2 is a vertical longitudinal sectional view therethrough, taken on the line 2-2 of Figure 1;

Figure 3 is a fragmentary vertical longitudinal sectional view, taken on the line 3-3 of Figure 1;

Figure 4 is a side elevation of the inner side of one of the end plates;

Figure 5 is a transverse vertical sectional view, taken on the line 5-5 of Figure 1;

Figure 6 is an end elevation of the spool showing the outer side of one of the end plates.

Specifically describing the embodiment of the invention illustrated in Figures 1-6, inclusive, the reference character 1 designates the body of the spool which is preferably in the form of a cylindrical tube, and the 55 reference characters 2 designate end plates

which are of a diameter somewhat greater than that of the body 1 to serve as flanges for the body to retain fabric or the like wound thereon. The plates 2 are substantially identical in construction and each is formed upon one side thereof with a co-axial annular groove 3 of a diameter corresponding to that of the tubular body 1, so that one end of said body may be fitted into each of said grooves.

Each of the end plates is also formed upon the side thereof in which the groove 3 is formed, with an integral co-axial boss 4 through which extends a threaded opening 5. Said boss is preferably formed by stamping or otherwise pressing the central portion of the plate from one side to the other, and the opening 5 may be formed at the same time and subsequently threaded; although the boss 4 and the threaded opening 5 may be formed in any other suitable manner. The side of each of the plates 2 opposite that of the boss 4 is formed with a countersink 6 surrounding the corresponding end of the opening 5, and this countersink may be formed in any suitable manner, for example by the pressing operation when the boss is formed by stamping the latter from the plate.

A tie member 7 which is preferably in the form of a tube has its ends threaded as at 8 to fit the openings 5. In assembling the spool, one end of the body 1 is fitted into the groove 3 of one of the end plates 2, the tie member 7 preferably having been first fitted into the opening 5 of the end plate. The other end plate 2 is then fitted upon the other end of the tie member 7 and screwed thereon until the corresponding end of the body 1 is fitted in the respective groove 3. By relative rotation of the end plates 2, the body is securely clamped between the end plates and the end plates securely fastened to each other. Obviously, the grooves 3 prevent lateral movement of the body 1 relative to the end plates, and the tie member 7 prevents separation of the end plates from each other and from the body. The ends of the tie member are then upset or flared, as at 9, into the respective countersinks 6 so that the plates 2 cannot be unscrewed from the tie member. It will be noted that the countersinks permit of easy upsetting or flaring of the ends of the tie member 7, and the upset portion is wholly beneath the plane of the corresponding end plate.

110

Preferably the body 1 is formed with a plurality of rows of perforations 10 and the end plates 2 are perforated as at 11. The body may also be formed with longitudinal 5 grooves or corrugations 12 in which the openings 10 are formed, so that the corrugations at the same time serve to strengthen the body 1 and as passages for liquid and air to and from the fabric on the spool.

10 While I have shown and described one preferred embodiment of my invention, it will be understood that this is primarily for the purpose of illustrating the principles of my invention, and that many modifications and 15 changes may be made in the details of construction of spools by those skilled in the art without departing from the spirit or scope of the invention. Therefore, I do not desire to be understood as limiting myself except 20 as required by the following claims when construed in the light of the prior art.

Having thus described the invention, what I claim is:

1. A spool comprising a substantially 25 cylindrical tubular body, a pair of end plates of a diameter greater than that of said body and each having a central threaded opening and a countersink around one end of said opening, said plates each having a groove on

its face opposite said countersink to receive 30 one end of said body, and a tie member extending co-axially through said body and having its end portions threaded and each fitted into said opening in one of said end plates and its extremity upset into the corresponding countersink so as to overlie said end plate with the upset portion below the plane of the corresponding side of said end plate.

2. A spool comprising a substantially 40 cylindrical tubular body, a pair of end plates of a diameter greater than that of said body and each having an integral co-axial boss on one side thereof and a threaded opening extending through the plate centrally of said boss, each of said plates also having on one side thereof a countersink surrounding said opening, means on said end plates for supporting said body co-axially therebetween, and a tie member extending co-axially 45 through said body and having its end portions threaded and each fitted into said opening in one of said end plates and its extremity upset into the corresponding countersink so as to overlie said end plate 50 with the upset portion below the plane of the corresponding side of said end plate.

HENRY BRUCKER.
